POLISHING PAD

Russell B. Kingman, Orange, N. J.

Application January 6, 1937, Serial No. 119,206

17 Claims. (Cl. 91—54.7)

This invention relates to a novel polishing pad structure of the type having a self-contained supply of polishing agent, such e. g. as a quantity of wax paste, wax powder or other polishing medium, cleansing agent or the like; such pad structure providing a hand manipulatable polishing medium applicator adapted to gradually exude and spread the polishing material upon a surface over which the pad is rubbed.

10 This invention has for an object to provide, as a complete article of manufacture ready for use, a novel wax or like containing pad structure which is of low production cost, while nevertheless being highly efficient for the intended purposes. To this end the pad structure is provided with a novel means for holding and supporting its content of wax paste or the like subject to gradual expression from the pad under the pressure applied thereto by the act of rubbing and moving the pad over a surface desired to be treated. This novel wax holding and supporting means comprises preferably flexible or pliant corrugated sheet material, in grooves or channels of which is deposited the wax paste. Said 15 corrugated holder and supporting means may be combined with a suitable backing or with suitable enclosing means; means being provided through which the wax paste may be expressed from the grooves or channels when the pad is in use.

A further object of this invention is to provide a waxing or like pad structure of the general character above mentioned having either a single operative face or provided in a reversible form having a plurality of selectively usable operative faces; and the invention also contemplates the provision of wax impervious means to initially protect the operative or effective faces of the pad structure while at the same time sealing the wax content of the pad against accidental escape or deterioration of the wax content thereof.

Other objects of this invention, not at this time more particularly enumerated, will be understood from the following detailed description of the same.

Illustrative embodiments of this invention are shown in the accompanying drawing, in which:—

50 Fig. 1 is a transverse vertical sectional view of a simple form of the novel waxing or like pad made according to the principles of this invention; Fig. 2 is a longitudinal vertical sectional view of the same, taken on line 2—2 in Fig. 1; 55 and Fig. 3 is a fragmentary transverse vertical

sectional view of a somewhat modified arrangement of said simple form of pad.

Fig. 4 is a transverse vertical sectional view of another form of the novel waxing or like pad of the reversible type. 5

Fig. 5 is a transverse vertical sectional view of a modified construction of the waxing or like pad embodying the principles of this invention, the same being of the non-reversible type. 10

Fig. 6 is a transverse vertical sectional view of another modified form and arrangement of waxing or like pad of the reversible type.

Figs. 7 and 8 are respectively fragmentary transverse vertical sectional views of other modified forms of the waxing or like pad within the 15 principles of this invention.

In the novel waxing pads according to this invention, the wax supporting means comprises corrugated holder sheet or sheets 11 made of more or less flexible or pliant material, which may be 20 grease-proof or impervious to wax, although in some cases, especially when the holder sheet is enclosed in an enveloping external covering, it is immaterial whether the same is impervious to wax or not. In fact, in some constructions of 25 the novel pad, it may be advantageous that the holder sheet be of pervious material. Generally, however, it is preferable to make the holder sheet of comparatively strong paper, such e. g. as manila, craft or the like. The corrugated holder sheet 11 provides on one or both faces a series of 30 spaced grooves or channels which form pockets or holding spaces 12 into which is filled a wax paste 13 of suitable consistency, such as a mixture of wax and a solvent therefor. 35

Referring to Figs. 1 and 2, there is shown there- 40 in a simple form of the novel waxing pad, comprising a corrugated holder sheet 11 having the holding spaces 12 on one side or face thereof filled with the wax paste 13. To the wax charged side or face of the holder sheet is affixed a back- 45 ing member 14, preferably of a more or less pliant character and of wax impervious material. The marginal portions 15 of the holder sheet 11 and the marginal portions 16 of the backing mem- 50 ber 14 are registered in meeting relation and secured together by a suitable glue or by any other method or means adapted to fasten and seal these parts together, whereby the holder sheet and backing member are retained in assembled 55 relation and the ends of the wax filled spaces 12 closed against escape of wax therethrough. The outwardly facing bottom walls of the wax filled corrugations 12 of the holder sheet, which, in the arrangement shown in Figs. 1 and 2 are ex- 55

posed to provide the working face of the pad, are provided with a plurality of spaced wax discharge perforations or vents 17. Initially the outwardly presented face of the pad thus formed 5 is covered by a removable wax impervious cover sheet 18; this cover sheet being preferably made of transparent cellulosic material such as known to trade by the name "Cellophane". The wax exposed at the perforations or vents 17 of the 10 pad will be sufficient to adhere and retain the cover sheet in place until removed. If desired, however, a light spotting of glue of a character sufficient to hold the cover sheet against accidental displacement while not resistant to 15 normal detachment thereof may be employed. The cover sheet 18, when in place, will hermetically seal the perforations or vents 17 against escape of volatile constituents of the wax paste and consequent undue hardening or other de- 20 terioration of the wax content of the pad. If interruption of the use of the pad occurs before entire consumption of its wax paste content, the cover sheet 18 may be replaced over the working face of the pad in closing and sealing relation the wax vents or perforations 17. If desired, a handle loop 19 may be suitably secured to the 25 backing member 14.

In the use of the simple form of waxing pad above described, the cover sheet 18 is removed 30 prior to application of the pad to a surface to be waxed. Having removed the cover sheet 18, the operative face of the pad is applied to and rubbed over the surface desired to be treated. As the pad is pressed against the surface to be 35 treated, the convex apical portions of the wax holder sheet will contact said surface and will present thereto the wax vents or perforations 17. The pressure exerted upon the back of the pad, together with the lateral movements induced by the reciprocation of the pad over the 40 surface upon which it is rubbed, by reason of the somewhat flexible or pliable character of the material of which the holder sheet 11 is made, causes both a squeezing and a lateral swaying movement or play of the wax containing 45 corrugations of said holder sheet. Such movements effect a kneading or working of the wax content of the holding spaces 12, which assures exudation of some of the wax through the vents or perforations 17 for deposit upon the 50 surface treated, over which surface the wax is spread by the wiping travel of the pad as a whole back and forth upon said surface. It will be obvious that the spaced corrugations of the holder sheet 11 serve to segregate the wax content of 55 the pad into individual masses upon which the kneading or working effects are exerted to best advantage. By reason of the kneading or working effects, a wax paste of normally compara- 60 tively stiff consistency may be employed, since said effects quickly operate to soften the paste adjacent the vents or perforations 17 so as to assure exudation thereof without undue tendency to express a quantity of the wax in excess 65 of that required to properly coat the surface under treatment.

The corrugations of the holder 11, which impinge upon the backing member 14 may be affixed to the latter, as e. g. by a suitable glue or cement, or by mechanical fastening means. If desired, however, these corrugations which impinge upon the backing member may be unattached to the latter; in which case a greater scope of swaying or lateral play and consequent 70 wax kneading movement of the wax holding cor-

rugations will be permitted. If the latter arrangement is employed, the holder sheet 11 will be attached to the backing member 14 only along its marginal edge portions.

As an alternative to the simple form of waxing pad shown in Figs. 1 and 2, I have shown a modified form thereof in Fig. 3, wherein instead of utilizing the inwardly facing grooves or channels of the corrugated holder sheet 11 as the wax holding spaces or chambers, I employ the outwardly facing grooves or channels for this purpose, thereupon covering the same with a facing sheet 20 which closes over the wax filled spaces 12. This facing sheet may be of textile fabric material or of any other suitable wax previous material, or it may be of paper or the like; in the latter case it will be provided with vents or perforations 20' aligned along and communicating with the wax filled spaces 12.

Referring to Fig. 4, there is shown therein a 20 waxing pad which embodies the principles of this invention but which further includes a construction adapted to provide a reversible form of pad; either face of which may be used at will.

This form of pad comprises the corrugated holder sheet 11, the spaced grooves or channels on both sides or faces of which are utilized as wax holding spaces or chambers 12 which are filled with the wax paste 13 or other polishing or cleansing agent. The holder sheet in this arrangement is interposed between two facing sheets 21 and 22, the respective marginal portions 23 and 24 of which extend beyond the periphery of the holder sheet and are brought together and secured by glue or cement, or by any suitable mechanical fastening means, thus enveloping said holder sheet and its wax content. The facing sheets 21 and 22 may be made of textile fabric material or of any other suitable wax previous material, or they may be made of paper 40 or the like, in which case the same will be provided with vents or perforations 25 aligned along and communicating with the adjacent wax filled spaces 12. The facing sheets 21-22, as thus applied and joined together, constitute an enclosing envelope for the holder sheet 11. Secured to opposite margins of this envelope are hand attachment straps 26 and 27, the free ends of which may be secured together by a coupling buckle 28 or other suitable joining means. It will be obvious that said straps 26 and 27 may be joined to form a hand attachment loop selectively extendible across one or the other of the operative faces of the pad, according to which face of the latter is to be freely presented for 50 application to a surface to be treated. The fixed or anchored ends of the straps 26 and 27 may be interposed and secured between the meeting marginal portions 23-24 of the facing sheets by the same means which serves to join and secure 55 said marginal portions together, thus providing a very simple and economical method of construction. Initially the facing sheets 21 and 22 are covered by removable wax impervious cover sheets 29, which serve both to initially close and 60 seal the wax vents 25, and also as a backing and protection against the escape of wax from that face of the pad use of which is reserved while the opposite face of the pad is in use. The cover sheet 29 on the reserved face of the pad also 65 protects the hands of the user from contact with wax. It will be obvious that after wax has, in use, been completely discharged from one side of this form of pad, the pad attachment straps 70 75

may be reversed, the cover sheet 29 on the reserved or second side of the pad may be removed and applied, if desired, over the first used or discharged side of the pad, whereupon said reversed 5 side of the latter will be exposed for use until it too is discharged of its wax content. In the use of this form of the pad, the pressure and lateral play effective upon the corrugations of the holder sheet will also produce the wax kneading 10 or working effects calculated to assure the desired gradual exudation of the wax content thereof.

In Fig. 5 I have shown a pad construction of non-reversible form, but having an arrangement 15 of holder sheet means calculated to provide a larger wax content capacity, than does the simple arrangement of holder sheet means shown in Figs. 1 and 2. In the construction shown in Fig. 5, two corrugated holder sheets 11 are arranged in superposed relation with interior grooves or channels thereof opposed in register or alignment to thereby provide double capacity wax holding spaces or chambers 12 in which the wax paste 13 is lodged. The margins 30 of the 20 holder sheets 11 are brought together in meeting relation and secured, as by glue or cement, or by other fastening means. The holder sheet structure thus provided is backed on one side by a wax impervious backing member 31 suitably secured thereto. If desired, a hand attachment 25 loop 32 may be secured to and across said backing member. The convex apical portions of the corrugations exposed along the opposite face of the holder sheet arrangement are provided with 30 a plurality of spaced vents or perforations 17 through which the wax may be discharged when the pad is in use. The pad thus formed may be provided, in secured and covering relation to its working face, with a facing sheet 33 of textile 35 fabric or other wax pervious material. The use of such facing sheet is optional.

In Fig. 6 I have shown another form of the novel waxing pad adapted to provide a large wax content capacity; as shown the pad is of the reversible type. In this construction, a plurality of holder sheets 11 are arranged in superposed relation with interior grooves or channels thereof opposed in register or alignment. All the grooves or channels on both faces of each so 45 arranged holder sheet 11 are constituted wax holding spaces or chambers 12 and are filled with the wax paste 13. The holder sheet arrangement is enclosed between facing sheets 34 and 35, the marginal portions of which are extended beyond 50 said holder sheet arrangement and are brought together and secured one to the other, thus forming an enclosing envelope around said holder sheet arrangement. If desired reversible hand loop straps 36 and 37 are secured to opposite 55 margins of the pad, the free ends of said straps being detachably coupled together by a suitable fastener 38. The side walls of the corrugations of the respective holder sheets are provided with 60 openings or perforations 39 whereby communication is established between the inner and outer wax holding spaces or chambers 12, so that when the pad is used, and under pressure and kneading or working effects similar to those already described, the wax will be gradually fed from 65 inner to outer spaces or chambers as consumption from the outer spaces or chambers occurs by reason of discharge of wax therefrom when the pad is in use. In this modified pad structure, instead of employing wax impervious sheet 70 material for the corrugated holder means and

providing therein the intercommunicating openings or perforations 39, said corrugated holder means may be made of wax pervious material, such e. g. as muslin or a more or less stiffened porous textile fabric. The facing sheets 34 and 5 35 are provided with a plurality of wax discharging vents or perforations 40 which communicate with the respective outer wax filled spaces or chambers of the holder sheets. Each facing sheet 34 and 35 is initially covered over 10 with a detachable wax impervious cover sheet 41 which closes and seals the underlying wax discharge vents or perforations 40. It will be obvious that while one working face of this type of pad is in use the other or second face thereof 15 is in reserve, but may be used when desired by reversing the pad. Although but two holder sheets have been shown relative to the last described form of the pad, it will be apparent that more than two holder sheets may be superimposed to form the wax supporting and carrying means thereof.

Other variations in the form and arrangement of the pads, but including the basic element of a corrugated wax holder sheet structure, are possible. Illustrative of some of such further variations, I have shown in Figs. 7 and 8 additional modified forms of reversible pad types. In Fig. 7 the pad structure comprises an intermediate or partition sheet 42 of wax impervious material. Upon opposite sides of said partition sheet 42 are superposed corrugated holder sheets 11, the outwardly facing grooves or channels of which constitute the holding spaces or chambers 12 to contain the wax paste 13. Over the 20 outer side of each holder sheet 11 is applied a facing sheet 43 which closes over the wax filled spaces 12. Said facing sheets 43 are provided with vents or perforations 44 aligned along and communicating with the wax filled spaces 12. If 25 desired, a wax pervious outer facing sheet 45 of textile fabric may be secured over each facing sheet 43. In Fig. 8 the pad structure comprises an intermediate or partition sheet 46 of wax impervious material. Upon opposite sides of said 30 partition sheet 46 are superposed corrugated holder sheets 11, the inwardly facing grooves or channels 12 to contain the wax paste 13. Provided in the outwardly presented convex apical portions of the wax filled corrugations of the 35 holder sheets 11 are a plurality of spaced wax discharge vents or perforations 47. If desired, the outer faces of the holder sheets 11 may be covered with a layer 48 of wax pervious textile fabric of any suitable character. If desired, 40 this fabric layer or cover may be made of terry cloth or other pile napped material. Removable cover sheets of wax impervious material, such e. g. as wax paper, glassine paper, Cellophane or the like may be employed for the purposes hereinbefore referred to. It will be obvious that, in the use of pads of the type shown in Figs. 7 and 45 8, the wax impervious intermediate or partition sheets serve to back the particular wax holder sheet which is applied for the discharge of its 50 wax content upon a surface to be treated; the same operating to transfer pressure in use to the wax content so as to discharge the same, while corrugations are subject to the same lateral play or movement effective to produce the desired 55 kneading or working of the wax content in aid of operative exudation thereof.

It will be obvious that many other variations and modifications of the novel pad structure, other than those already hereinabove referred 60

to, could be made without departing from the scope of this invention as defined in the here-following claims. Hence, I do not limit this invention to the exact arrangements and combinations of the constructions, materials, or parts described in the foregoing specification or shown in the accompanying drawing, consequently such disclosures are to be considered as illustrative and not in a limiting sense.

10 1. I claim:—

1. A pad having an expressible polishing agent content, comprising corrugated holder means, channels of which provide holding chambers, masses of polishing agent within said holding chambers, and means through which said polishing agent may be gradually expressed from said holding chambers by pressure and movement imparted to the pad in use.

2. A pad having an expressible polishing agent content, comprising corrugated holder means, channels of which provide holding chambers, masses of polishing agent within said holding chambers, means impervious to said polishing agent adapted to back said corrugated holder means, and means through which said polishing agent may be gradually expressed from said holding chambers by pressure and movement imparted to the pad in use.

3. A pad having an expressible polishing agent content, comprising corrugated holder means of pliant sheet material, channels of which provide holding chambers, masses of polishing agent within said holding chambers, a backing means to support said corrugated holder means, said backing means being impervious to said polishing agent, means through which said polishing agent may be gradually expressed from said holding chambers by pressure and movement imparted to the pad in use, and a removable impervious cover sheet to initially close the latter means.

4. A pad having an expressible polishing agent content, comprising corrugated holder means, channels of which provide holding chambers, masses of polishing agent within said holding chambers, means through which said polishing agent may be gradually expressed from said holding chambers by pressure and movement imparted to the pad in use, and a removable impervious cover sheet to initially close the latter means.

5. A pad having an expressible polishing agent content, comprising corrugated holder means of pliant sheet material, channels of which provide holding chambers, masses of polishing agent within said holding chambers, and means to envelop said corrugated holder means, said enveloping means being pervious to the gradual exudation of the polishing agent therethrough under pressure and movement imparted to the pad in use.

6. A pad having an expressible polishing agent content, comprising corrugated holder means of pliant sheet material, channels of which provide holding chambers, masses of polishing agent within said holding chambers, means to envelop said corrugated holder means, said enveloping means being pervious to the gradual exudation of the polishing agent therethrough under pressure and movement imparted to the pad in use, and external detachable cover means superposed on said enveloping means to initially seal said pervious enveloping means against the expression of polishing agent therethrough.

7. A pad having an expressible polishing agent content, comprising corrugated holder means of pliant sheet material, channels on opposite faces

of which provide holding chambers, masses of polishing agent within said holding chambers, means to envelop said corrugated holder means, said enveloping means being pervious to the gradual exudation of the polishing agent therethrough under pressure and movement imparted to the pad in use, and opposite faces of said enveloping means being selectively usable as polishing agent applicator surfaces.

8. A pad having an expressible polishing agent content, comprising corrugated holder means of pliant sheet material, channels on opposite faces of which provide holding chambers, masses of polishing agent within said holding chambers, means to envelop said corrugated holder means, said enveloping means being pervious to the gradual exudation of the polishing agent therethrough under pressure and movement imparted to the pad in use, opposite faces of said enveloping means being selectively usable as polishing agent applicator surfaces, and a reversible hand attachment loop means connected with said pad for selective operative disposition relative to either face of said pad.

9. A pad having an expressible polishing agent content, comprising corrugated holder means of pliant sheet material, channels on opposite faces of which provide holding chambers, masses of polishing agent within said holding chambers, means to envelop said corrugated holder means, said enveloping means being pervious to the gradual exudation of the polishing agent therethrough under pressure and movement imparted to the pad in use, opposite faces of said enveloping means being selectively usable as polishing agent applicator surfaces, and external detachable impervious cover means superposed on each face of said pervious enveloping means to initially seal said faces against the expression of polishing agent therethrough.

10. A pad having an expressible polishing agent content, comprising corrugated holder means of pliant sheet material, channels on opposite faces of which provide holding chambers, masses of polishing agent within said holding chambers, means to envelop said corrugated holder means, said enveloping means being pervious to the gradual exudation of the polishing agent therethrough under pressure and movement imparted to the pad in use, opposite faces of said enveloping means being selectively usable as polishing agent applicator surfaces, external detachable impervious cover means superposed on each face of said pervious enveloping means to initially seal said faces against the expression of polishing agent therethrough, and a reversible hand attachment loop means connected with said pad for selective operative disposition relative to either face of said pad.

11. A pad having an expressible polishing agent content, comprising corrugated holder means of pliant sheet material, channels of which provide holding chambers, masses of polishing agent within said holding chambers, an impervious backing member of pliant material applied over one face of said holding means, marginal portions of said holder means and backing member being affixed together in secured relation, the corrugations of said holder means being subject to compressible and lateral movement adapted to effect a kneading or working of the polishing agent contained in channels thereof when said pad is in use, and means through which said polishing agent may be gradually expressed from

said channels by pressure and movement imparted to the pad in use.

12. A pad having an expressible polishing content, comprising corrugated holder means of pliant sheet material, channels of which provide holding chambers, masses of polishing agent within said holding chambers, an impervious backing member of pliant material applied over one face of said holding means, marginal portions of said holder means and backing member being affixed together in secured relation, the corrugations of said holder means being subject to compressible and lateral movement adapted to effect a kneading or working of the polishing agent contained in channels thereof when said pad is in use, means through which said polishing agent may be gradually expressed from said channels by pressure and movement imparted to the pad in use, and a hand attachment loop connected to and externally across said backing member.

13. A pad having an expressible polishing agent content, comprising corrugated holder means of pliant sheet material, channels of which provide holding chambers, masses of polishing agent within said holding chambers, an impervious backing member of pliant material applied over one face of said holding means, marginal portions of said holder means and backing member being affixed together in secured relation, the corrugations of said holder means being subject to compressible and lateral movement adapted to effect a kneading or working of the polishing agent contained in channels thereof when said pad is in use, means through which said polishing agent may be gradually expressed from said channels by pressure and movement imparted to the pad in use, and an external detachable impervious cover means superposed on the polishing agent exuding surfaces of said pad to initially seal said surfaces against the expression of polishing agent therethrough.

14. A pad having an expressible polishing agent content, comprising corrugated holder means of pliant sheet material, channels of which provide holding chambers, masses of polishing agent within said holding chambers, an impervious backing member of pliant material applied over one face of said holding means, marginal portions of said holder means and backing member being affixed together in secured relation, the corrugations of said holder means being subject to compressible and lateral movement adapted to effect a kneading or working of the polishing agent contained in channels thereof when said pad is in use, means through which said polishing agent may be gradually expressed from said

channels by pressure and movement imparted to the pad in use, an external detachable impervious cover means superposed on the polishing agent exuding surfaces of said pad to initially seal said surfaces against the expression of polishing agent therethrough, and a hand attachment loop connected to and externally across said backing member.

15. A pad having an expressible polishing agent content, comprising corrugated holder members of pliant sheet material, outwardly facing channels of which provide holding chambers, masses of polishing agent within said holding chambers, a sheet of impervious material intermediate said holder members, the corrugations of said holder members being subject to compressible and lateral movements adapted to effect a kneading or working of the polishing agent contained in channels thereof when said pad is in use, and means through which said polishing agent may be gradually expressed from said channels by pressure and movement of the pad in use.

16. A pad having an expressible polishing agent content, comprising corrugated holder members of pliant sheet material outwardly facing channels of which provide holding chambers, masses of polishing agent within said holding chambers, a sheet of impervious material intermediate said holder members, the corrugations of said holder members being subject to compressible and lateral movements adapted to effect a kneading or working of the polishing agent contained in channels thereof when said pad is in use, means through which said polishing agent may be gradually expressed from said channels by pressure and movement of the pad in use, and external facing means of textile fabric on the operative surfaces of said pad.

17. A pad having an expressible polishing agent content, comprising corrugated holder members of pliant sheet material, outwardly facing channels of which provide holding chambers, masses of polishing agent within said holding chambers, a sheet of impervious material intermediate said holder members, the corrugations of said holder members being subject to compressible and lateral movements adapted to effect a kneading or working of the polishing agent contained in channels thereof when said pad is in use, means through which said polishing agent may be gradually expressed from said channels by pressure and movement of the pad in use, and external detachable impervious cover means superposed on the polishing agent exuding surfaces of said pad to initially seal said surfaces against the expression of polishing agent therethrough.

RUSSELL B. KINGMAN.
